UNITED STATES PATENT OFFICE.

ALONZO J. SARGENT, OF JACKSON, MICHIGAN.

OAR-LOCK.

1,335,606.

Specification of Letters Patent. Patented Mar. 30, 1920.

Application filed July 31, 1919. Serial No. 314,454.

To all whom it may concern:

Be it known that I, ALONZO J. SARGENT, a citizen of the United States, residing at Jackson, in the county of Jackson and State 5 of Michigan, have invented certain new and useful Improvements in Oar-Locks, of which the following is a specification.

This invention relates to an improved detachable oar lock and has as one of its 10 principal objects to provide a device of this character which may be conveniently carried about and to this end will be provided with elements which may be folded so that the device will occupy a minimum space.

15 The invention has as a further object in this connection to provide a device having foldable supporting arms but wherein said arms will, when in active position, be locked against movement.

20 And a still further object of the invention is to provide a device which may be readily attached to or detached from the gunwale of a boat and adapted, when in position, to support an oar stirrup above the 25 gunwale so that such stirrup will not wear against the gunwale.

Other and incidental objects will appear hereinafter.

In the drawings:

30 Figure 1 is a plan view showing my improved device applied to the gunwale of a boat, the gunwale being conventionally illustrated,

35 Fig. 2 is a perspective view showing the device detached,

Fig. 3 is a fragmentary sectional view taken on the line 3--3 of Fig. 1, and

40 Fig. 4 is a fragmentary sectional view taken at substantially right angles to Fig. 3, centrally through the device.

Fig. 5 is a fragmentary view of the topmost portion of supporting arm 14.

In carrying the invention into effect, my improved device is formed with a cylindrical stirrup socket or barrel 10 from opposite sides of which project pairs of spaced lugs, the uppermost of which are indicated at 11 while the lower lugs of said pairs are indicated at 12. The uppermost lugs 11 are somewhat thicker than the lower lugs and formed in the lugs 11 are medial alined slots 13 opening through the outer ends of the lugs and extending radially with respect to the socket 10. In this connection, it is to be observed that the socket is open at its ends. Swingly mounted upon the socket are

lateral supporting arms 14 provided at their outer ends with enlarged angularly disposed feet 15. Formed on the inner ends of said arms are spaced lugs 16 freely received between the pairs of lugs 11 and 12. Upstanding from the uppermost of the lugs 16 are ribs 17 and removably engaging through the lugs of the socket and the lugs 16 of said arms are pivot pins 18 detachably and 65 swingingly connecting the arms with the socket.

Integrally formed on the socket at substantially right angles to the plane of the lugs 11 and 12 are clamping arms 19 and 70 20 respectively. These arms curve downwardly and inwardly beneath the socket and formed on the inner end of the arm 19 is a laterally enlarged head 21. At its lower end, the arm 20 carries a cylindrical head 75 22 through which is threaded a clamp screw 23 and swiveled upon the inner end of said screw is a clamping plate 24 confronting the head 21 of the arm 19. Formed on the socket at opposite sides of the arm 19 are 80 stop lugs 25 and formed on the lowermost of the lugs 16 of the arms 14 are stop lugs 26 adapted to coact with the lugs 25 for limiting the arms in their outward swinging movement to alined position.

It is now to be observed that the ribs 17 of the arms 14 are adapted to engage within the slots 13 for locking the arms in alined active position extending at opposite sides of the stirrup socket 10. Consequently, the 90 device may then, as shown in Fig. 1, be fitted upon the gunwale of a boat to engage the arms with the upper edge of said gunwale. In this figure the gunwale of a boat has been conventionally illustrated at 27. 95 The arms will thus support the device upon the gunwale in such position that the head 21 of the arm 19 will confront the outer face of the gunwale while the plate 24 upon the clamping screw 23 will confront the inner face of the gunwale. Accordingly, the clamping screw may be operated for securely clamping the device upon the gunwale. The socket is adapted to carry any conventional type of oar stirrup as conventionally shown at 28 in the drawings. The shank of the stirrup is rotatably fitted through the socket in the usual manner, and if desired, a length of chain 29 may be employed to prevent accidental loss of the 110 stirrup. As will be noted, the arms are of a length to extend well below the lower end

of the stirrup socket for supporting the socket spaced above the upper edge of the gunwale so that the shank of the stirrup will not contact with the gunwale to wear there-
5 against. Furthermore, it is to be particu-
larly noted that since, when the arms 14 are
in active position they are locked against
swinging movement, lateral displacement of
the arms from engagement with the gun-
10 wale will be prevented. I accordingly pro-
vide a device which, as will be at once ap-
preciated, may be readily attached to the
gunwale of substantially any conventional
type of row boat and which will provide a
15 firm support for an oar. If desired, the arm
19 may be provided with spaced keeper lugs
30 for removably receiving, as suggested in
dotted lines in Fig. 3, the needle of a fish
stringer. In this way a string of fish may
20 be allowed to trail in the water while, at the
same time, being conveniently connected
with the boat.

Particular attention is now directed to
the fact that the arms 14 are mounted to
25 move vertically upon the pivot pins 18. Consequently, when the device is detached,
the arms will normally drop downwardly
upon said pivot pins to disengage the lugs
17 from within the slots 13. Thus, the
30 arms may be folded inwardly to lie along
the sides of the arm 20, so that the device
will occupy a minimum space and accord-
ingly may be easily carried about. I, there-
fore, provide a particularly convenient type
35 of portable oar lock.

Having thus described the invention, what
is claimed as new is:

1. A device of the class described includ-
ing an open-ended stirrup socket, support-
40 ing arms extending downwardly from said
socket and terminating below the inner end
of the socket, clamping arms projecting
downwardly from the socket, and clamping
means carried by one of said clamping arms
45 and adjustable thereon to coöperate with the
other for connecting the device with a boat.

2. The combination with a boat having a
gunwale, of an oar lock for the boat includ-
ing a stirrup socket, supporting arms pro-
50 jecting downwardly from the socket and
seating against the upper edge of the gun-
wale for supporting the inner end of the
socket above the gunwale, clamping arms
extending from the socket at opposite sides
55 of the gunwale, and clamping means adjust-
able upon one of said arms to coöperate with
the other for engagement with the gunwale
to connect the device with the boat.

3. A device of the character described in-
60 cluding an open-ended stirrup socket, arms

extending from the socket and terminating
below the inner end thereof for supporting
the inner end of the socket above the plane
of the free ends of said arms, clamping arms
projecting from the socket and terminating
65 in a plane below the free extremities of said
first mentioned arms, and clamping means
carried by one of said clamping arms and
adjustable thereon to coöperate with the
other for connecting the device with a boat. 70

4. A device of the character described in-
cluding a stirrup socket, supporting arms
swingly connected thereto, and means
for connecting the device with a boat.

5. A device of the character described in-
cluding a stirrup socket, supporting arms
swingly connected thereto, means for
locking the said arms in active position, and
means for connecting the device to a boat.

6. A device of the character described in-
cluding a stirrup socket, supporting arms
swingly connected thereto, coacting
means carried by said arms and the socket
respectively for locking the arms in active
80 position, and means for connecting the de-
vice with a boat.

7. A device of the character described in-
cluding a stirrup socket, lugs carried there-
by and provided with slots, arms swingly
connected with the socket and provided with
90 ribs engageable in said slots for locking the
arms in active position, and means for con-
necting the device with a boat.

8. A device of the character described in-
cluding a stirrup socket, pairs of lugs car-
ried thereby, supporting arms for the socket,
pivot pins swingly connecting the arms
with said pairs of lugs, certain of said lugs
100 being provided with slots, ribs carried by the
arms, the arms being movable longitudinally
of said pivot pins to engage the lugs thereof
within said slots for locking the arms in ac-
tive position, and means for connecting the
device with a boat.

9. A device of the character described, in-
cluding a stirrup socket, supporting arms
swingly connected thereto, means for
connecting the device with a boat, and means
for limiting the arms in their swinging
105 movement to active position.

10. A device of the character described in-
cluding a stirrup socket provided with lugs,
supporting arms swingly connected to
the socket and provided with lugs engage-
able with the first lugs for limiting the arms
in their swinging movement to active posi-
110 tion, and means for connecting the device
with a boat.

In testimony whereof I affix my signature.
ALONZO J. SARGENT. [L.S.]
